QUATERNARY SALTS OF BASIC ESTERS OF
 β -(1-NAPHTHYL)-ACRYLIC ACID

Silvano Casadio, Milan, Italy, assignor to Istituto de
Angeli S.p.A., Milan, Italy, an Italian body corporate
No Drawing. Filed Oct. 20, 1965, Ser. No. 499,614

ABSTRACT OF THE DISCLOSURE

This invention relates to quaternary salts of basic esters of β -(1-naphthyl)-acrylic acid having valuable antibacterial and antifungal activities. The quaternary salts of the invention possess the general formula

wherein R¹ is hydrogen or phenyl, R² and R³ individually represent methyl or ethyl or when taken collectively with the nitrogen atom to which they are attached represent morpholino, piperidino or pyrrolidino; R⁴ represents methyl, ethyl, butyl, isoamyl, octyl, decyl, dodecyl, hexadecyl, octadecyl, bromohexyl, benzyl or an acetyl and X represents a bromide, chloride or iodide ion or a methyl sulphate ion.

According to the present invention, there are provided compounds of the general formula:

in which:

R¹ represents a hydrogen atom or an aryl group;
R² and R³, which may be the same or different, each represents an alkyl group or R² and R³, together with the adjacent nitrogen atom, represents a heterocyclic group which may if desired contain a further hetero atom;
R⁴ represents an alkyl, haloalkyl, aralkyl or acyl group; and

X represents an associated anion e.g. a halide or alkylsulphate ion.

As stated above, the compounds according to the invention have valuable antibacterial and antifungal activities

2

and are particularly intended for the topical treatment of bacterial and fungal infections. In compounds of the Formula I in which R¹ represents an aryl group, it preferably represents a phenyl group. When R² and R³ represent alkyl groups, they advantageously represent alkyl groups containing from 1 to 6 carbon atoms; where R² and R³ together with the adjacent nitrogen atom represent a heterocyclic group, this is advantageously a 5- or 6-membered saturated heterocyclic group such as for example a pyrrolidino, piperidino or morpholino group. R⁴ preferably represents an alkyl group containing from 1 to 20 carbon atoms (e.g. a methyl, ethyl, butyl, isoamyl, octyl, decyl, dodecyl, hexadecyl or octadecyl group), a bromoalkyl group such as for example a 6-bromo-hexyl group; a benzyl group; or an acetyl group. X preferably represents a chlorine, bromine or iodine atom, or a methyl sulphate group.

Particularly preferred compounds according to the invention by virtue of their especially valuable antibacterial and antifungal activities are compounds of the Formula I in which R⁴ represents an alkyl group containing from 8 to 12 carbon atoms such as, for example, the following:

- (a) 2-(dimethylamino)ethyl β -(1-naphthyl)-acrylate dodecyl bromide,
- (b) 2-(N-pyrrolidino)ethyl β -(1-naphthyl)-acrylate decyl bromide,
- (c) 2-(N-morpholino)ethyl β -(1-naphthyl)-acrylate decyl bromide, and
- (d) 1-phenyl-2-(N-piperidino)ethyl β -(1-naphthyl)-acrylate decyl bromide.

Of these compounds, compound (b) is particularly preferred for use in medicinal preparations.

The antibacterial activity of compounds according to the invention may be demonstrated by "in vitro" tests utilising the dilution technique (1:2 in tryptose phosphate broth [Difco]) against the following microorganisms: *Bacillus subtilis* ATCC 6633, *Micrococcus pyogenes*, var. *aureus* ATCC 6538P, *Streptococcus haemolyticus* C203 America, *Escherichia coli* McLeod ATCC 10536, *Proteus vulgaris* ATCC 7829 and *Pseudomonas aeruginosa* ATCC 10145. 18-24 hours old cultures of the microorganisms, suitably diluted, were inoculated with the compounds to be tested and, after incubation for 24 hours at 37° C., the minimum concentration of compound which effected inhibition of the growth of the microorganisms was estimated.

The antifungal activity of compounds according to the invention has been demonstrated by "in vitro" tests utilising the dilution technique (1:2 in Sabourauds medium) against the following microorganisms: *Candida albicans* ATCC 10231, *Trichophyton mentagrophytes* ATCC 8757 and *Saccharomyces cerevisiae* ATCC 9763. With *Candida albicans* and *Saccharomyces cerevisiae* incubation was effected, after inoculation of the compounds to be tested, for a period of 24 hours prior to estimation of the minimum inhibitory concentration; with *Trichophyton mentagrophytes*, the incubation period was five days.

In the following table, the results of tests carried out on the compounds (a), (b), (c) and (d) according to the invention are summarised. These tests were carried out by means of the suspension technique according to the method of Said and coll. described in *Annales pharm. franc.* 21, 187, 1963, and the results demonstrate the bac-

tericidal and fungicidal activities of the four compounds even at very low concentrations.

(wherein R¹, R² and R³ are as hereinbefore defined). The reaction is advantageously carried out in an organic sol-

Compound	Bactericidal activity minimum inhibitory concentration in g./1,000 ml					Fungicidal activity, in- hibitory con- centration in g./1,000 ml.

(b)-----	0.0004	0.0001	0.0016	0.0008	0.0008	0.0004
(c)-----	0.0004	0.0001	0.0016	0.0008	0.0008	0.0004
(d)-----	0.0001	0.00005	0.0032	0.0008	0.0008	0.0004

Compounds according to the invention have also been tested on rabbits eyes and by subcutaneous injection into the abdomen of mice in order to ascertain the suitability of the compounds for topical application. These tests demonstrated that the compounds according to the invention have good skin compatibility.

Further according to the invention, there is provided a process for the preparation of compounds of the Formula I which comprises reacting an amine of the general formula

with a quaternising agent to introduce the substituent R^4 and the anion X^- .

The quaternising agent will in general be a compound of the formula R^4X' , where X' is a halide or alkyl sulphate ion. Where it is desired that the final compound have an anion other than halide or alkyl sulphate this may be achieved by conventional ion-exchange techniques.

The reaction is conveniently carried out in the presence of an organic solvent such as, for example, benzene, toluene, acetone or acetonitrile, advantageously at a temperature between 20 and 50° C. The reaction time will generally vary between 2 and 60 days according to the nature of the reactants used. The quaternary salts of Formula I are in general relatively insoluble in the organic solvent medium and slowly precipitate in crystalline form; in some cases, however, it is desirable to remove the solvent in order to isolate the product. The compounds of Formula I obtained may be purified in any convenient way, for example by washing with ether.

The compounds of Formula II used as starting materials in the above-described process according to the invention may be prepared in any convenient manner, e.g. by one of the following methods:

(1) Reaction of the corresponding β -(1-naphthyl)-acrylic chloride with an aminoalcohol of formula:

(wherein R¹, R² and R³ are as hereinbefore defined). The reaction is preferably carried out in the presence of an organic solvent such as for example ether, benzene or dioxan under substantially anhydrous conditions and in the presence of an acid-binding agent such as, for example, an excess of the aminoalcohol of Formula IV. The reaction mixture is advantageously refluxed for 2-4 hours to effect the reaction.

(2) Reaction of the sodium β -(1-naphthyl)-acrylate with a chloroamine of formula:

15 vent such as for example ethanol or propanol, refluxing the reaction mixture for 15-24 hours.

The compounds of Formula II may be viscous liquids of pale yellow colour or white crystalline solids, insoluble in water but soluble in the common organic solvents and in aqueous acid solutions. Several of the compounds of Formula II useful as starting materials are now compounds.

The compounds of Formula I according to the invention are in general colourless crystalline solids having varying solubilities in water. The quaternary salts formed with benzyl chloride, methyl chloride, butyl bromide and isoamyl bromide are for example soluble in water whilst the salts formed with longer chain alkyl halides are either insoluble or only sparingly soluble in water.

Further according to the invention there are provided pharmaceutical compositions (and especially compositions adapted for topical use) which comprise at least one compound of the Formula I in association with a pharmaceutical carrier or excipient. The compositions according to the invention may for example be suitable for application to the skin, or alternatively may be adapted for use in the nose, ear or mouth. The compositions may for example be in the form of ointments, creams, mouth washes, nasal and otological drop solutions, alcoholic tinctures, powders for topical use, vaginal tablets and suppositories, spray solutions and the like. Preferred compositions according to the invention contain from 0.02 to 1.5% by weight of the compound or compounds of Formula I. If desired, the compositions according to the invention may also contain further therapeutic compounds in addition to compounds of the Formula I, for example anti-inflammatory steroids (e.g. prednisolone, triamcinolone, betamethazone or dexamethasone), antibiotics especially suitable for topical administration (e.g. neomycin) and local anaesthetics (e.g. xylocaine).

In order that the invention may be well understood, the following examples are given by way of illustration only:

EXAMPLE 1

19.8 g. of β -(1-naphthyl)-acrylic acid and 50 ml. of thionyl chloride are refluxed for 1 hour. The excess of thionyl chloride is distilled off at reduced pressure and the oily residue is redissolved in 20 ml. of anhydrous benzene. 14.5 g. of 2-(N-piperidino)-ethanol in 20 ml. of anhydrous benzene are then slowly added to the benzene solution which is externally cooled during the addition in order not to allow the temperature to rise above 20° C. A further 20 ml. of anhydrous benzene are then added and the reaction mixture is refluxed for 3 hours. After cooling, the suspended solid is filtered, washed with benzene and crystallised from absolute ethanol. The 2-(N-piperidino)-ethyl β -(1-naphthyl)-acrylate hydrochloride is thus obtained (M. Pt. 197° C.).

70 The free base, obtained by treatment of an aqueous solution of the hydrochloride with alkali, is a viscous liquid of pale yellow colour boiling at 189–191° C./0.1 mm. Hg.

Analysis for $C_{20}H_{23}O_2N$ (percent). Calc.: C, 77.64; H, 7.49; N, 4.53. Found: C, 77.95; H, 7.53; N, 4.49.

The following compounds are prepared in an analogous manner:

2-dimethylaminoethyl β -(1-naphthyl)-acrylate

B.P. 170–175° C./0.2 mm. Hg.

Analysis for $C_{17}H_{19}O_2N$ (percent). Calc.: C, 75.81; H, 7.11; N, 5.20. Found: C, 76.3; H, 7.10; N, 5.39. Hydrochloride: M.P. 153° C.

2-(N-pyrrolidino)-ethyl β -(1-naphthyl)-acrylate

B.P. 197–199° C./mm. Hg.

Analysis for $C_{19}H_{21}O_2N$ (percent). Calc.: C, 77.26; H, 7.17; N, 4.74. Found: C, 77.50; H, 7.18; N, 4.88. Hydrochloride: M.P. 151° C.

1-phenyl-2-dimethylaminoethyl β -(1-naphthyl)-acrylate

M.P. 82–83° C. (crystallized from isopropanol. Analysis for $C_{23}H_{23}O_2N$ (percent). Calc.: C, 79.97; H, 6.71; N, 4.06. Found: C, 79.83; H, 6.82; N, 4.00. Hydrochloride: M.P. 181–183° C.

1-phenyl-2-(N-morpholino)-ethyl β -(1-naphthyl)-acrylate

M.P. 117° C. (crystallized from 95% ethanol). Analysis for $C_{25}H_{25}O_3N$ (percent). Calc.: C, 77.49; H, 6.50; N, 3.62. Found: C, 78.00; H, 6.59; N, 3.61. Hydrochloride: M.P. 200–204° C.

1-phenyl-2-(N-piperidino)-ethyl β -(1-naphthyl)-acrylate

M.P. 78–79° C. (crystallized from 95% ethanol). Analysis for $C_{26}H_{27}O_2N$ (percent). Calc.: C, 81.01; H, 7.06; N, 3.63. Found: C, 81.46; H, 7.11; N, 3.67. Hydrochloride: M.P. 191–192° C.

EXAMPLE 2

A suspension of 50 g. of sodium β -(1-naphthyl)-acrylate and 33.9 g. of 2-(N-morpholino)-1-chloroethane in 400 ml. of isopropanol is refluxed for 20 hours. The sodium chloride, formed during the reaction, is then filtered off in the warm. The crude 2-(N-morpholino)-ethyl β -(1-naphthyl)-acrylate crystallizes upon cooling and, after recrystallisation from isopropanol, melts at 80–82° C.

Analysis for $C_{19}H_{21}O_3N$ (percent). Calc.: C, 73.29; H, 6.80; N, 4.50. Found: C, 73.01; H, 6.81; N, 4.60. Hydrochloride: M.P. 213° C.

EXAMPLE 3

11 ml. of a 18% solution of methyl bromide in benzene are added to 4.1 g. of 2-dimethylaminoethyl β -(1-naphthyl)-acrylate in 10 ml. of anhydrous benzene and the mixture is maintained at room temperature for 2 days. The precipitate thus formed is separated by filtration, washed with benzene and then with ether. 2-dimethylaminoethyl β -(1-naphthyl)-acrylate methyl bromide is thus obtained as a white crystalline solid melting at 174° C.

Analysis for $C_{18}H_{22}O_2NBr$ (percent). Calc.: C, 59.35; H, 6.08; N, 3.84; Br, 21.94. Found: C, 60.12; H, 6.10; N, 3.91; Br, 22.05.

The following quaternary salts are prepared in an analogous manner:

2-dimethylaminoethyl β -(1-naphthyl)-acrylate
n.butyl bromide

Reaction time: 4 days, M.P. 186–188° C. Analysis for $C_{21}H_{28}O_2NBr$ (percent). Calc.: C, 62.06; H, 6.94; N, 3.45; Br, 19.66. Found: C, 62.36; H, 7.01; N, 3.39; Br, 19.15.

2-dimethylaminoethyl β -(1-naphthyl)-acrylate
isomayl bromide

Reaction time: 5 days, M.P. 182–186° C. Analysis for $C_{22}H_{30}O_2NBr$ (percent). Calc.: C, 62.87; H, 7.19; N, 3.33; Br, 19.01. Found: C, 62.01; H, 7.00; N, 3.31; Br, 19.11.

2-dimethylaminoethyl β -(1-naphthyl)-acrylate
6-bromohexyl bromide

Reaction time: 7 days, M.P. 189–190° C. Analysis for $C_{23}H_{31}O_2NBr_2$ (percent). Calc.: C, 53.8; H, 6.09; N, 2.73; Br, 31.14. Found: C, 53.91; H, 6.11; N, 2.69; Br, 31.01.

2-dimethylaminoethyl β -(1-naphthyl)-acrylate
n-octyl bromide

Reaction time: 7 days, M.P. 157–158° C. Analysis for $C_{25}H_{36}O_2NBr$ (percent). Calc. C, 64.93; H, 7.85; N, 3.03; Br, 17.28. Found: C, 64.95; H, 7.77; N, 3.03; Br, 17.41.

2-dimethylaminoethyl β -(1-naphthyl)-acrylate
n-decyl bromide

Reaction time: 12 days, M.P. 165–168° C. Analysis for $C_{27}H_{40}O_2NBr$ (percent). Calc.: C, 66.10; H, 8.22; N, 2.86; Br, 16.29; Found: C, 66.01; H, 8.19; N, 2.89; Br, 16.33.

2-dimethylaminoethyl β -(1-naphthyl)-acrylate
n-dodecyl bromide

Reaction time: 12 days, M.P. 156–158° C. Analysis for $C_{29}H_{44}O_2NBr$ (percent). Calc.: C, 67.20; H, 8.55; N, 2.70; Br, 15.41. Found: C, 67.41; H, 8.56; N, 2.69; Br, 15.45.

2-(N-morpholino)-ethyl β -(1-naphthyl)-acrylate
methyl bromide

Reaction time: 3 days, M.P. 175–177° C. Analysis for $C_{20}H_{24}O_3NBr$ (percent). Calc. C, 59.12; H, 5.95; N, 3.45; Br, 19.67. Found: C, 59.91; H, 5.88; N, 3.43; Br, 19.66.

2-(N-piperidino)-ethyl β -(1-naphthyl)-acrylate
methyl bromide

Reaction time: 2 days, M.P. 175° C. Analysis for $C_{21}H_{26}O_2NBr$ (percent). Calc.: C, 62.38; H, 6.48; N, 3.46; Br, 19.77. Found: C, 62.43; H, 6.43; N, 3.51; Br, 19.60.

2-(N-pyrrolidino)-ethyl β -(1-naphthyl)-acrylate
methyl bromide

Reaction time: 2 days, M.P. 178° C. Analysis for $C_{20}H_{24}O_2NBr$ (percent). Calc.: C, 61.54; H, 6.20; N, 3.59; Br, 20.47. Found: C, 61.10; H, 6.18; N, 3.51; Br, 20.39.

2-(N-pyrrolidino)-ethyl β -(1-naphthyl)-acrylate
n-butyl bromide

Reaction time: 6 days, M.P. 214–220° C. Analysis for $C_{23}H_{30}O_2NBr$ (percent). Calc.: C, 63.90; H, 6.99; N, 3.24; Br, 18.48. Found: C, 63.10; H, 6.88; N, 3.21; Br, 18.53.

2-(N-pyrrolidino)-ethyl β -(1-naphthyl)-acrylate
isoamyl bromide

Reaction time: 6 days, M.P. 213–218° C. Analysis for $C_{24}H_{32}O_2NBr$ (percent). Calc.: C, 64.56; H, 7.23; N, 3.14; Br, 17.90. Found: C, 64.59; H, 7.21; N, 3.11; Br, 17.50.

2-(N-pyrrolidino)-ethyl β -(1-naphthyl)-acrylate
6-bromohexyl bromide

Reaction time: 7 days, M.P. 80–100° C. Analysis for $C_{25}H_{33}O_2NBr_2$ (percent). Calc.: C, 55.60; H, 6.16; N, 2.59; Br, 29.63. Found: C, 55.99; H, 6.11; N, 2.58; Br, 29.50.

2-(N-pyrrolidino)-ethyl β -(1-naphthyl)-acrylate
n.octyl bromide

Reaction time: 8 days, M.P. 132–133° C. Analysis for $C_{27}H_{38}O_2NBr$ (percent). Calc.: C, 66.38; H, 7.84; N, 2.87; Br, 16.36. Found: C, 66.55; H, 7.81; N, 2.90; Br, 16.41.

1-phenyl-2-dimethylaminoethyl β -(1-naphthyl)-acrylate methyl bromide

Reaction time: 2 days, M.P. 218° C. Analysis for $C_{24}H_{26}O_2NBr$ (percent). Calc.: C, 65.48; H, 5.95; N, 3.18; Br, 18.15. Found: C, 65.91; H, 5.88; N, 3.18; Br, 18.67.

1-phenyl-2-dimethylaminoethyl β -(1-naphthyl)-acrylate dimethylsulphate

Reaction time: 14 days, M.P. 168–172° C. Analysis for $C_{25}H_{29}O_3NS$ (percent). Calc.: C, 63.68; H, 6.20; N, 2.97. Found: C, 62.9; H, 6.21; N, 2.84.

1-phenyl-2-dimethylaminoethyl β -(1-naphthyl)-acrylate methyl iodide

Reaction time: 2 days, M.P. 173–176° C. Analysis for $C_{24}H_{26}O_2NI$ (percent). Calc.: C, 59.12; H, 5.38; N, 2.87; I, 26.06. Found: C, 59.90; H, 5.29; N, 2.89; I, 26.19.

1-phenyl-2-dimethylaminoethyl β -(1-naphthyl)-acrylate n-butyl bromide

Reaction time: 20 days, M.P. 160–165° C. Analysis for $C_{27}H_{33}O_2NBr$ (percent). Calc.: C, 67.20; H, 6.69; N, 2.91; Br, 16.57. Found: C, 67.44; H, 6.55; N, 3.01; Br, 16.66.

1-phenyl-2-dimethylaminoethyl β -(1-naphthyl)-acrylate isoamyl bromide

Reaction time: 20 days at 50° C. The product was isolated by removal of the solvent. M.P. 84–88° C. Analysis for $C_{28}H_{34}O_2NBr$ (percent). Calc.: C, 67.73; H, 6.90; N, 2.82; Br, 16.10. Found: C, 67.91; H, 6.83; N, 2.86; Br, 16.44.

1-phenyl-2-dimethylaminoethyl β -(1-naphthyl)-acrylate 6-bromohexyl bromide

Reaction time: 7 days, M.P. 70–75° C. Analysis for $C_{29}H_{35}O_2NBr$ (percent). Calc.: C, 59.12; H, 5.99; N, 2.38; Br, 27.11. Found: C, 59.01; H, 6.03; N, 2.18; Br, 27.03.

1-phenyl-2-dimethylaminoethyl β -(1-naphthyl)-acrylate n-octyl bromide

Reaction time: 8 days, M.P. 82° C. Analysis for $C_{31}H_{40}O_2NBr$ (percent). Calc.: C, 69.13; H, 7.49; N, 2.60; Br, 14.84. Found: C, 69.51; H, 7.57; N, 2.59; Br, 14.99.

1-phenyl-2-dimethylaminoethyl β -(1-naphthyl)-acrylate n-decyl bromide

Reaction time: 20 days, M.P. 74–78° C. Analysis for $C_{33}H_{44}O_2NBr$ (percent). Calc.: C, 70.00; H, 7.82; N, 2.47; Br, 14.10. Found: C, 70.61; H, 7.94; N, 2.47; Br, 14.14.

1-phenyl-2-dimethylaminoethyl β -(1-naphthyl)-acrylate n-dodecyl bromide

Reaction time: 25 days, M.P. 98–102° C. Analysis for $C_{35}H_{48}O_2NBr$ (percent). Calc.: C, 70.7; H, 8.14; N, 2.36; Br, 13.44. Found: C, 70.8; H, 8.11; N, 2.40; Br, 13.39.

1-phenyl-2-(N-morpholino)-ethyl β -(1-naphthyl)-acrylate methyl bromide

Reaction time: 6 days, M.P. 206–107° C. Analysis for $C_{26}H_{28}O_3NBr$ (percent). Calc.: C, 64.73; H, 5.85; N, 2.90; Br, 16.57. Found: C, 64.50; H, 5.67; N, 2.74; Br, 16.57.

1-phenyl-2-(N-piperidino)-ethyl β -(1-naphthyl)-acrylate methyl bromide

Reaction time: 8 days, M.P. 212° C. Analysis for $C_{27}H_{30}O_2NBr$ (percent). Calc.: C, 67.50; H, 6.29; N, 2.91; Br, 16.63. Found: C, 67.39; H, 6.27; N, 2.70; Br, 16.91.

1-phenyl-2-(N-piperidino)-ethyl β -(1-naphthyl)-acrylate acetyl chloride

Reaction time: 2 days, M.P. 193–194° C. Analysis for $C_{28}H_{30}O_3NCl$ (percent). Calc.: C, 72.50; H, 6.52; N, 3.02; Cl, 7.64. Found: C, 72.81; H, 6.39; N, 3.18; Cl, 7.80.

EXAMPLE 4

3.62 g. of hexadecyl bromide are added, at 50° C., to 2.9 g. of 2-dimethylaminoethyl β -(1-naphthyl)-acrylate

dissolved in a mixture of 120 ml. of anhydrous acetonitrile and 10 ml. of anhydrous benzene and the solution thus obtained is maintained at 50° C. for 20 days. The solid thus formed is separated by filtration and then washed first with benzene and then with ether. The 2-dimethylaminoethyl β -(1-naphthyl)-acrylate hexadecyl bromide is thus obtained as a white crystalline solid melting at 157–160° C.

Analysis for $C_{33}H_{52}O_2NBr$ (percent). Calc.: C, 69.00; H, 9.12; N, 2.44; Br, 13.91. Found: C, 69.21; H, 9.10; N, 2.39; Br, 14.06.

The following quaternary ammonium salts are obtained in an analogous manner:

2-(N-morpholino)-ethyl β -(1-naphthyl)-acrylate n-butyl bromide

Reaction time: 5 days. The compound was isolated by removal of the solvent. M.P. 177–187° C. Analysis for $C_{23}H_{30}O_3NBr$ (percent). Calc.: C, 61.6; H, 6.74; N, 8.12; Br, 17.82. Found: C, 62.0; H, 6.77; N, 3.21; Br, 17.91.

2-(N-morpholino)-ethyl β -(1-naphthyl)-acrylate n-octyl bromide

Reaction time: 20 days, M.P. 86–88° C. Analysis for $C_{27}H_{33}O_2NBr$ (percent). Calc.: C, 64.28; H, 7.59; N, 2.78; Br, 15.84. Found: C, 65.00; H, 7.61; N, 2.70; Br, 15.89.

2-(N-morpholino)-ethyl β -(1-naphthyl)-acrylate n-decyl bromide

Reaction time: 60 days. The product was isolated by removal of the solvent. M.P. 88–92° C. Analysis for $C_{29}H_{42}O_3NBr$ (percent). Calc.: C, 65.40; H, 7.95; N, 2.63; Br, 15.01. Found: C, 65.10; H, 7.88; N, 2.67; Br, 15.15.

2-(N-morpholino)-ethyl β -(1-naphthyl)-acrylate n-dodecyl bromide

Reaction time: 60 days. The product was isolated by removal of the solvent. M.P. 76–80° C. Analysis for $C_{31}H_{46}O_3NBr$ (percent). Calc.: C, 66.40; H, 8.27; N, 2.50; Br, 14.26. Found: C, 66.93; H, 8.31; N, 2.50; Br, 14.38.

2-(N-piperidino)-ethyl β -(1-naphthyl)-acrylate n-octyl bromide

Reaction time: 8 days, M.P. 155–157° C. Analysis for $C_{28}H_{40}O_2NBr$ (percent). Calc.: C, 66.92; H, 8.02; N, 2.79; Br, 15.90. Found: C, 66.18; H, 8.01; N, 2.81; Br, 15.66.

2-(N-pyrrolidino)-ethyl β -(1-naphthyl)-acrylate n-decyl bromide

Reaction time: 20 days, M.P. 92.95° C. Analysis for $C_{29}H_{42}O_2NBr$ (percent). Calc.: C, 67.45; H, 8.20; N, 2.71; Br, 15.47. Found: C, 67.91; H, 8.19; N, 2.83; Br, 15.41.

2-(N-pyrrolidino)-ethyl β -(1-naphthyl)-acrylate n-dodecyl bromide

Reaction time: 25 days, M.P. 90–95° C. Analysis for $C_{31}H_{46}O_2NBr$ (percent). Calc.: C, 68.40; H, 8.52; N, 2.57; Br, 14.67. Found: C, 68.10; H, 8.55; N, 2.59; Br, 14.55.

2-(N-pyrrolidino)-ethyl β -(1-naphthyl)-acrylate n-octadecyl bromide

Reaction time: 25 days, M.P. 82–86° C. Analysis for $C_{37}H_{56}O_2NBr$ (percent). Calc.: C, 70.68; H, 9.30; N, 2.23; Br, 12.71. Found: C, 70.00; H, 9.19; N, 2.18; Br, 12.75.

1-phenyl-2-dimethylaminoethyl β -(1-naphthyl)-acrylate n-octadecyl bromide

Reaction time: 45 days. The compound was isolated by removal of the solvent. M.P. 82–86° C. Analysis for

$C_{41}H_{60}O_2$ NBr (percent). Calc.: C, 72.52; H, 8.92; N, 2.06; Br, 11.77. Found: C, 72.80; H, 8.99; N, 2.15; Br, 11.51.

1-phenyl-2-(N-piperidino)-ethyl β -(1-naphthyl)-acrylate n-octyl iodide

Reaction time: 20 days. The product was isolated by removal of the solvent. M.P. 158–163° C. Analysis for $C_{34}H_{44}O_2NI$ (percent). Calc.: C, 65.28; H, 7.09; N, 2.24; I, 20.29. Found: C, 65.53; H, 7.12; N, 2.25; I, 20.23.

1-phenyl-2-(N-piperidino)-ethyl β -(1-naphthyl)-acrylate n-decyl bromide

Reaction time: 20 days, M.P. 168–171° C. Analysis for $C_{36}H_{48}O_2NBr$ (percent) Calc.: C, 71.30; H, 7.98; N, 2.31; Br, 13.17. Found: C, 71.48; H, 8.05; N, 2.47; Br, 13.21.

EXAMPLE 5

1.28 g. of benzyl chloride are added to a solution of 2.87 g. of 2-dimethylaminoethyl β -(1-naphthyl)-acrylate in 5 ml. of anhydrous acetone and the solution maintained at room temperature for 2 days. The solid which thus separates is separated by filtration and washed with ether. The 2-dimethylaminoethyl β -(1-naphthyl)-acrylate benzyl chloride is thus obtained as a white crystalline solid melting at 197–198° C.

Analysis for $C_{24}H_{26}O_2NCl$ (percent). Calc.: C, 72.80; H, 6.62; N, 3.55; Cl, 8.95. Found: C, 72.51; H, 6.60; N, 3.57; Cl, 9.01.

The following quaternary ammonium salts are obtained in an analogous manner:

2-(N-morpholino)-ethyl β -(1-naphthyl)-acrylate benzyl chloride

Reaction time; reaction temperature: 5 days at 50° C. M.P. 166–167° C. Analysis for $C_{26}H_{28}O_3NCl$ (percent). Calc.: C, 71.30; H, 6.44; N, 3.20; Cl, 8.09. Found: C, 70.99; H, 6.43; N, 3.12; Cl, 8.13.

2-(N-piperidino)-ethyl β -(1-naphthyl)-acrylate benzyl chloride

Reaction time: 5 days, M.P. 189–191° C. Analysis for $C_{27}H_{30}O_2NCl$ (percent). Calc.: C, 74.38; H, 6.94; N, 3.21; Cl, 8.13. Found: C, 74.42; H, 6.99; N, 3.19; Cl, 8.16.

2-(N-pyrrolidino)-ethyl β -(1-naphthyl)-acrylate benzyl chloride

Reaction time: 5 days, M.P. 176° C. Analysis for $C_{26}H_{28}O_2NCl$ (percent). Calc.: C, 74.01; H, 6.69; N, 3.32; Cl, 8.40. Found: C, 74.62; H, 6.83; N, 3.31; Cl, 8.39.

1-phenyl-2-dimethylaminoethyl β -(1-naphthyl)-acrylate benzyl bromide

Reaction time: 15 days. Reaction temperature: 50° C. The compound was isolated by removal of the solvent. M.P. 60–65° C. Analysis for $C_{30}H_{30}O_2NBr$ (percent). Calc.: C, 69.75; H, 5.85; N, 2.71; Br, 15.47. Found: C, 69.95; H, 5.72; N, 2.58; Br, 15.39.

1-phenyl-2-dimethylaminoethyl β -(1-naphthyl)-acrylate benzyl chloride

Reaction time: 20 days, M.P. 178–181° C. Analysis for $C_{30}H_{30}O_2NCl$ (percent). Calc.: C, 76.34; H, 6.41; N, 2.97; Cl, 7.51. Found: C, 76.34; H, 6.31; N, 2.79; Cl, 7.61.

1-phenyl-2-(N-piperidino)-ethyl β -(1-naphthyl)-acrylate benzyl chloride

Reaction time: 20 days. Reaction temperature: 50° C., M.P. 105–110° C. Analysis for $C_{33}H_{34}O_2NCl$ (percent). Calc.: C, 77.40; H, 6.69; N, 2.73; Cl, 6.92. Found: C, 77.10; H, 6.80; N, 2.75; Cl, 6.84.

EXAMPLE 6.—TINCTURES

(a) For pre-operative skin disinfectant:	2-(N-pyrrolidino)-ethyl β -(1-naphthyl)-acrylate			
5	n-decyl bromide	g	0.5	
	70% alcohol, q.s. to	ml	100	
(b) 2-(N-pyrrolidino)-ethyl β -(1-naphthyl)-acrylate			1	
5	n-decyl bromide	g		
	Industrial methylated spirits	ml	75	
	Distilled water, q.s. to	ml	100	

EXAMPLE 7.—AQUEOUS SOLUTIONS

(a) For pre-operative skin disinfectant:	2-(N-pyrrolidino)-ethyl β -(1-naphthyl)-acrylate			
15	n-decyl bromide	g	1	
	Propylene glycol	ml	5	
	Distilled water, q.s. to	ml	100	
(b) Disinfectant for the hands and arms of the surgeon before surgical procedures:	A	B		
20	2-(N-pyrrolidino)-ethyl β -(1-naphthyl)-acrylate	g	0.5	0.1
	n-decyl bromide	g		
	Propylene glycol	ml	5	5
	Distilled water, q.s. to	ml	100	100
(c) Disinfectants for use in obstetrics and for burns and wounds:				
25	2-(N-pyrrolidino)-ethyl β -(1-naphthyl)-acrylate	g	0.05	
	n-decyl bromide	g		
	Propriophylene glycol	ml	5	
	Distilled water, q.s. to	ml	100	

EXAMPLE 8.—CREAMS

		Grams		
		A	B	
35	(a) 2-(N-pyrrolidino)-ethyl β -(1-naphthyl)-acrylate	0.5	0.1	
	n-decyl bromide	g		
	Cetostearyl alcohol	10	10	
	Liquid paraffin	10	10	
	Distilled water, q.s. to	100	100	
(b) 2-(N-pyrrolidino)-ethyl β -(1-naphthyl)-acrylate	0.5	0.1		
40	n-decyl bromide	g		
	Polyethylene 1000 monocetyl ether	2	2	
	Cetostearyl alcohol	8	8	
	Cetyl alcohol	5	5	
	Yellow soft paraffin	10	10	
	Liquid paraffin	10	10	
	Glycerin	5	5	
	Distilled water, q.s. to	100	100	

EXAMPLE 9.—LOTIONS

		Grams		
		A	B	
50	2-(N-pyrrolidino)-ethyl β -(1-naphthyl)-acrylate	0.5	0.1	
	n-decyl bromide	g		
	Wool fat	3	3	
	Cetyl alcohol	2	2	
	Liquid paraffin	20	20	
55	Glycerin	2	2	
	Distilled water, q.s. to	100	100	

EXAMPLE 10.—VAGINAL TABLETS

		Grams		
		A	B	
60	Each tablet contains:			
	2-(N-pyrrolidino)-ethyl β -(1-naphthyl)-acrylate	0.005	0.0005	
	n-decyl bromide	g		
	Polyisobutylene 80	0.010	0.010	
	Lactose, q.s. to	2	2	

EXAMPLE 11.—VAGINAL SUPPOSITORIES

		Grams		
		A	B	
70	Each suppository contains:			
	2-(N-pyrrolidino)-ethyl β -(1-naphthyl)-acrylate	0.005	0.0005	
	n-decyl bromide	g		
	Glycerinated gelatine, q.s. to	2	2	

EXAMPLE 12.—LOZENGES

	Grams	
	A	B
Each lozenge contains:		
2-(N-pyrrolidino)-ethyl β -(1-naphthyl)-acrylate n-decyl bromide	0.002	0.0005
Mannitol	0.200	0.200
Talc	0.020	0.020
Flavour, q.s.		
Sugar, q.s. to	1	1

EXAMPLE 13.—EAR DROPS

	A	B
2-(N-pyrrolidino)-ethyl β -(1-naphthyl)-acrylate n-decyl bromide, g.	0.5	0.02
Propylene glycol (ml.), q.s. to	100	100

I claim:

1. A compound of the formula

wherein R¹ is selected from the group consisting of a hydrogen atom and a phenyl group; R² and R³ taken individually represent a group selected from the group consisting of methyl and ethyl, or when taken collectively with the nitrogen atom to which they are attached represent a heterocycle selected from the group consisting of piperidino, morpholino and pyrrolidino; R⁴ is selected

from the group consisting of methyl, ethyl, butyl, isoamyl, octyl, decyl, dodecyl, hexadecyl, octadecyl, a bromohexyl, benzyl and an acetyl group; and X is selected from the group consisting of a chloride ion, a bromide ion, an iodide ion and a methyl sulfate ion.

5 2. 2-(dimethylamino)ethyl β -(1-naphthyl)-acrylate do-

decyl bromide.

3. 2-(N-pyrrolidino)ethyl β -(1-naphthyl)-acrylate de-

cyl bromide.

10 4. 2-(N-morpholino)ethyl β -(1-naphthyl)acrylate de-

cyl bromide.

5. 1-phenyl-2-(N-piperidino)ethyl β -(1-naphthyl)-acry-

late decyl bromide.
